UNITED STATES PATENT OFFICE.

ALICE LA GUAYRA MAYO, OF GREAT FALLS, MONTANA TERRITORY.

HEMMING ATTACHMENT FOR SEWING-MACHINES.

SPECIFICATION forming part of Letters Patent No. 414,914, dated November 12, 1889.

Application filed August 14, 1888. Serial No. 282,733. (No model.)

To all whom it may concern:

Be it known that I, ALICE LA GUAYRA MAYO, of Great Falls, in the county of Cascade and Territory of Montana, have invented 5 a new and Improved Presser-Foot Hemmer, of which the following is a full, clear, and exact description.

My invention relates to an improvement in hemmers, and is especially designed for hemming all articles that require a wider hem than the ordinary fell; and the object of the invention is to provide a device which will turn a hem from, for instance, a quarter of an inch to about seven and a half or eight 15 inches in width, and also to provide a means whereby a draw-string, ribbon or tape may be inserted in the hem; and the further object of the invention is to provide a hemmer which will have a double gage and be constructed in a simple, durable, and thoroughly 20 practical manner.

The invention consists in the construction and combination of the several parts, as will be hereinafter fully set forth, and pointed out 25 in the claims.

Reference is to be had to the accompanying drawings, forming a part of this specification, in which similar letters of reference indicate corresponding parts in all the figures.

Figure 1 is a perspective view of the hemmer, and Fig. 2 is a side elevation of the same. Fig. 3 is a view showing the attachment in position during the operation of turning a hem and inserting a ribbon or tape.

In carrying out the invention, A represents a body-bar provided with a vertically-apertured post A', integral with the upper face near one end and at one side, into which post 40 the presser-bar of the machine is secured through the medium of a set-screw a, passing through said post to a contact with the needle-bar. The said post A' is provided upon one side with a recess a' intersecting the bore or 45 aperture adapted for the reception of the needle-bar, which recess a' is purposed to accommodate the presser-foot.

The frame of the hemmer consists of two side bars B and B', the side bar B being the 50 wider of the two and provided with a longitudinal slot b and a scale of inches b', produced upon the upper face, preferably at the

outer edge. The side bar B is made to rest in a suitable recess formed transversely in the upper face of the body-bar A at or near 55 the end of said bar, as best illustrated in Fig. 1, the said side bar B being adjustably held in connection with the body-bar through the medium of a set-screw b², passing through the slot b of the side bar into the body-bar; 60 but if it is found desirable in practice the set-screw b² may be substituted by a rivet, the rivet being so located as to permit the side bar B to readily yet not too freely slide upon the body-bar. The opposing side bar 65 B' is passed through a transverse slot produced in the body-bar at or near the end, to which the slotted side bar B is secured, and the two side bars B and B' are pivotally connected at their outer ends by a cross-bar C, 70 which cross-bar rests upon the upper surface of the said side bars, as illustrated in the drawings. A forward cross or guide bar D is formed integral with the slotted side bar B, extending at right angles therefrom a distance beyond the smaller side bar B'. The 75 said inner guide or cross bar D is bent downward upon itself at right angles to form a vertical flange d, whereby the said guide-bar partakes of the contour of an angle-iron. A 80 second and under guide-bar E, which more properly may be designated a "retaining-bar," is formed integral with the narrow side bar B', extending at right angles thereto in direction of the slotted side bar B and beneath and in engagement with the horizontal member of the guide-bar D, as best illustrated in Fig. 1. The retaining-bar E is also continued beyond the outer edge of the side 85 bar B' to support the extension of the guide-bar D. Between the post A' and the side bar 90 B' the hemmer proper H is secured to the edge of the body-bar contiguous to the guide-bar D, which hemmer may be of any desired construction, but is formed of one or two 95 pieces of metal, preferably the latter, bent so as to represent in cross-section the letter U, and having one under edge turned upward and inward to curl over the fabric as it passes through to receive the stitch.

In operation the body-bar is slid upon the side bar until the inner face of the said body-bar is made to register with the inch or fraction of the inch to which the hem is to be turned.

The material is then passed under the entire frame and body-bar, carried down in direction of the guide-bar, and passed over the retaining-bar and beneath the guide-bar and into 5 the hemmer. A ribbon or tape may be inserted in the hem by placing the same beneath the gage. In lace it can be used as a border, and in heavy material as a draw-string. Space must be left to remove the 10 gages, and in very wide hems the hemmer should be removed from the machine.

Having thus described my invention, what I claim as new, and desire to secure by Letters Patent, is—

- 15 1. The combination, with the body-bar A, provided with an apertured post adapted to receive the presser-bar, and a hem-former H, secured to the said body-bar, of an adjustable frame consisting of a slotted side bar B, 20 having a scale produced thereon, adjustably secured to the body-bar, a transverse-angled guide-bar D, secured to the slotted side bar, an opposing narrower side bar B', sliding in

the body-bar, a transverse retaining-bar secured to the said narrow side bar, engaging 25 the under face of the guide-bar, and a cross-bar C, pivotally securing one end of the said side bars, all combined to operate substantially as and for the purpose specified.

2. As a new article of manufacture, a hem- 30 mer attachment for sewing-machines, consisting of the body-bar A, provided with an apertured post adapted to receive the presser-bar of the sewing-machine, and a hem-former secured thereto, an adjustable frame consisting of slotted side bar B, having a guide-bar D at one end, an opposing side bar B', provided with a retaining-bar engaging the guide-bar, and a pivoted cross-bar C, all adapted to operate substantially as and for the purpose 35 40 described.

ALICE LA GUAYRA MAYO.
